UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

GUN TRAIL-CARRIAGE WITH ENDLESS TRACKS.

1,320,801.

Specification of Letters Patent.

Patented Nov. 4, 1919.

Application filed February 28, 1919. Serial No. 279,878.

To all whom it may concern:

Be it known that I, EUGÈNE SCHNEIDER, a citizen of the French Republic, and a resident of 42 Rue d'Anjou, Paris, France, 5 have invented new and useful Improvements in Gun Trail-Carriages with Endless Tracks, which invention is fully set forth in the following specification.

This invention has for its object to provide an improved gun carriage having a single-trail, mounted on endless tracks, the trail being capable of turning on the anchorage of the trail tail as a pivot for the purpose of training the gun. The carriage 10 proper comprises a platform on which a gun pedestal is pivoted. The trail is mounted on trunnions in the usual manner in said pedestal. The said platform is supported by a framing that stays together the endless- 15 track trucks.

In accordance with this invention the said framing is provided with a guide shaped according to the arc of a circle for the training movements of the platform. This guide 20 has its center at the axis of the trail pivot. An actuating mechanism, such as a worm, journaled in the framing and engaging with a toothed sector formed on the platform, enables the platform to be moved on the 25 framing.

A constructional form of this invention is illustrated by way of example in the accompanying drawings in which:

Figure 1 is a side elevation, partly in 35 vertical section along the axis of the trail, of the gun carriage in position for firing.

Fig. 2 is a corresponding plan.

Fig. 3 is a cross section on the line III-III of Fig. 1.

In the example shown, the improved gun carriage comprises a trail A in which the cradle B, that carries the gun barrel C, is mounted on trunnions in the usual manner. 40 The trail is journaled by means of an axle

D in a gun pedestal E having a pivot pin E¹ mounted rotatably in the center of a platform F. This platform is supported by a framing G which stays together the two endless-track trucks J and K. The trail A 45

is arranged to be capable of pivoting on an anchorage for the trail tail, consisting for instance of a platform H provided with a pivot pin I with which the tail eye a is en-

gaged. The platform H is anchored to the ground in the usual manner by means of stakes h.

According to the present invention the framing G is provided with a curved guide, that is to say, a guide G¹-G² having the shape of an arc of a circle centered at the axis of the pivot pin I. The trail is shown in position for firing, that is to say, situated at right angles to the endless tracks. The platform F may be engaged with the underside of the guides G¹, G² by means of lips F¹, F² of corresponding curvature. For the purpose of training the gun through small angles, the platform F, the gun pedestal E and the trail A are rotated as a whole around the pivot pin I, without shifting 65 the endless tracks or the platform G that stays the latter together. This rotation may be effected for instance by means of the mechanism shown which comprises a worm L journaled in the framing G, and engaging with a toothed sector M that is concentric with the guide G¹-G² and is formed or fitted on the platform F. A hand crank L¹ is fixed on the shaft of the worm L for the purpose of rotating the platform F in the 70 desired direction.

The framing G may be provided at its ends with devices g for the attachment of any suitable means of traction, for the purpose of rotating the gun carriage as a whole 75 around the pivot pin I when it is desired to train the gun through a large angle.

In the constructional form shown in the drawing, the movement of the platform F in the guide G¹-G² is facilitated by the 80 provision on the framing G of conical tracks G³, G⁴, which are concentric with the guide, and over which are adapted to run truncated conical rollers N whose axles are journaled in brackets O on which the platform F rests elastically.

What I claim is:-

1. A single-trail gun carriage with endless tracks, of the type wherein the trail is adapted to pivot around the trail-tail anchorage for the purpose of training the gun, comprising a movable platform on which is pivoted a gun pedestal and carried by a framing that stays the endless-track trucks together, characterized by the features that 105 the said framing is provided with a guide,

- in the shape of an arc of a circle, for the said platform, said circle having its center at the axis of the pivot pin of the trail.
2. A gun carriage as claimed in claim 1, comprising an actuating mechanism including a worm journaled in the framing, and engaging with a toothed sector formed on the platform, for the purpose of shifting the said platform in the said framing.
- 10 3. A gun carriage as claimed in claim 1, wherein the curved guide for the platform comprises concentric conical tracks for truncated conical rollers journaled in brackets on which the platform rests elastically.
- 15 4. In a trail gun carriage provided with endless tracks and adapted to pivot around an axis at the trail-tail anchorage, a framing connecting the trucks of the endless tracks and provided with an arc-shaped guide, and a gun-carrying platform movable on said guide.
- 20 5. In a trail gun carriage provided with endless tracks and adapted to pivot around an axis at the trail-tail anchorage, a framing connecting the trucks of the endless tracks and provided with an arc-shaped guide having its center at said axis, a platform movable on said guide about said axis, and a gun pedestal pivotally mounted on said platform.
- 25 6. In a trail gun carriage provided with endless tracks and adapted to pivot around an axis at the trail-tail anchorage, a framing connecting the trucks of the endless tracks and provided with an arc-shaped guide, a gun-carrying platform movable on said guide, and means to move said platform with respect to said framing.
- 30 7. In a trail gun carriage provided with
- endless tracks and adapted to pivot around an axis at the trail-tail anchorage, a framing connecting the trucks of the endless tracks and provided with an arc-shaped guide, a gun-carrying platform movable on said guide, a sector on said platform, and a worm journaled on said framing for operating said sector to move said platform.
- 35 8. In a trail gun carriage provided with endless tracks and adapted to pivot around an axis at the trail-tail anchorage, a framing connecting the trucks of the endless tracks and provided with an arc-shaped guide, a gun-carrying platform movable on said guide, and rollers intermediate said platform and framing.
- 40 9. In a single-trail gun carriage provided with endless tracks and adapted to pivot around an axis at the trail-tail anchorage, a framing connecting the trucks of the endless tracks and provided with an arc-shaped guide, a gun-carrying platform movable on said guide, conical tracks on said framing concentric with said guide, and conical rollers on said platform coacting with said conical tracks.
- 45 10. In a trail gun-carriage provided with endless tracks and adapted to pivot around an axis at the trail-tail anchorage, a framing connecting the trucks of the endless tracks and provided with an arc-shaped guide, a gun-carrying platform movable on said guide, tracks on said framing concentric with said guide, rollers on said platform coacting with said tracks, and elastic means intermediate said rollers and platform.

In testimony whereof I have signed this specification.

EUGÈNE SCHNEIDER.
